UNITED STATES PATENT OFFICE.

EMERY L. COOK, OF GREENCASTLE, INDIANA, ASSIGNOR OF ONE-HALF
TO CHAS. D. MITCHELL, OF GREENCASTLE, INDIANA.

RAIL-JOINT.

No. 824,285.

Specification of Letters Patent.

Patented June 26, 1906.

Application filed April 28, 1906. Serial No. 314,237.

To all whom it may concern:

Be it known that I, EMERY L. COOK, a citizen of the United States, residing at Green-
castle, in the county of Putnam and State of
Indiana, have invented certain new and use-
ful Improvements in Rail-Joints, of which the
following is a specification.

The present invention has for its primary
object to provide an improved rail-joint by
means of which adjacent rail-sections can be
readily connected in such a manner as to be
securely held against any relative movement,
either in a vertical or horizontal direction.

A further object is to construct the joint in
a peculiar manner, so that the continuity of
the tread portion will not be broken by the
expansions and contractions which take
place.

For a full description of the invention and
the merits thereof and also to acquire a knowl-
edge of the details of construction of the
means for effecting the result reference is to
be had to the following description and ac-
companying drawings, in which—

Figure 1 is a perspective view of the im-
proved rail-joint. Fig. 2 is a vertical longi-
tudinal sectional view through the same.
Fig. 3 is a vertical sectional view. Fig. 4 is a
detail perspective view of the rail ends when
detached, and Fig. 5 is a horizontal longi-
tudinal sectional view through the joint.

Corresponding and like parts are referred to
in the following description and indicated in
all the views of the drawings by the same ref-
erence characters.

The numerals 1 and 2 designate the abut-
ting ends of two rail-sections, which may be of
any conventional form and are shown as hav-
ing a standard-section. The web portions of
the rail ends are enlarged at 3, so as to corre-
spond approximately in thickness to the
width of the treads of the rails. A tenon 4 of
approximately rectangular shape projects
outwardly from the enlarged portion 3 of the
rail end 1, and the enlarged portion of the web
of the rail end 2 is provided with a recess 5,
adapted to receive the tenon 4. The upper
portion of the end 1 is formed with a V-
shaped tongue or projection 6, which is

spaced from the tenon 4 and which forms a 50
continuation of the tread of the rail. A de-
pression 7, corresponding in shape to the
tongue 6, is formed in the head of the rail-sec-
tion 2.

In order to form a rigid connection be- 55
tween the two rail ends, a bolt 8 is employed,
which passes through corresponding openings
9 in the opposite sides of the recess 5 and an
opening 10 in the tenon 4, which registers
with the openings 9 when the rail ends are 60
brought together into normal position. It
will be observed that the openings 9 in the
sides of the recess 5 are elongated, so that the
bolt 8 has a slight play, which enables the
rails to contract and expand in the usual man- 65
ner. Attention is called to the fact that the
portion of the bolt 8 adjacent the head is
formed with wings 11 and that the ends of the
openings 9 adjacent the end of the rail-sec- 70
tion 2 have an angular formation and are 70
adapted to engage with the wings 11 to hold
the bolt 8 against turning. It may be found
desirable under certain conditions, as when
the joint occurs between two ties, to employ
a chair 12 of the type shown, which com- 75
prises a base-plate having the longitudinal
edges bent upwardly to embrace the flanges
of the rails. Owing to the fact that the
tongue 6 has a V-shaped formation, it will be
apparent that the slight movements of the 80
tongue within the depression 7, due to the ex-
pansions and contractions of the rails, will
not be sufficient to break the continuity of
the tread.

Having thus described the invention, what 85
is claimed as new is—

In a rail-joint, the combination of two
abutting rail ends, the webs of the rail ends
being enlarged at the joint so as to corre- 90
spond in thickness to the width of the tread, a
tenon of approximately rectangular forma-
tion projecting from the web portion of one of
the rail ends and fitting in a corresponding
recess in the web portion of the opposite rail
end, a V-shaped tongue projecting from the 95
head of one of the rail ends and spaced from the
before-mentioned tenon, the head of the oppo-
site rail-section being formed with a V-shaped

depression for the reception of the tongue, and a bolt passing through corresponding openings in the sides of the before-mentioned recess in the web of one of the rail-sections 5 into which a tenon fits, and also through an opening in the tenon which registers with the corresponding openings when the two ends of the rails are brought together, the said corre-

sponding openings being elongated to permit of the expansion and contraction of the rails. 10

In testimony whereof I affix my signature in presence of two witnesses.

EMERY L. COOK. [L. s.]
